United States Patent Office

Des. 176,441
Patented Dec. 27, 1955

176,441

SURFACE COMPARATOR

Olin W. Boughton, Canandaigua, N. Y., assignor to
Bausch & Lomb Optical Company, Rochester, N. Y.,
a corporation of New York

Application May 6, 1955, Serial No. 35,858

Term of patent 14 years

(Cl. D52—1)

FIG. 1

FIG. 2

FIG. 3

FIG. 4

Fig. 1 is a perspective view taken from the left side of a surface comparator, showing my new design.

Fig. 2 is a perspective view of the same, taken from a different angle.

Fig. 3 is a bottom plan view thereof.

Fig. 4 is an elevational view of the hinge end thereof.

I claim:

The ornamental design for a surface comparator, substantially as shown.
